INVENTOR.

Frederick M. Furber

UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

BELT-SHIFTER.

1,136,116.

Specification of Letters Patent.

Patented Apr. 20, 1915.

Application filed July 15, 1914. Serial No. 851,192.

To all whom it may concern:

Be it known that I, FREDERICK M. FURBER, a citizen of the United States, residing at Revere, in the county of Suffolk and State 5 of Massachusetts, have invented certain Improvements in Belt-Shifters, of which the following description, in connection with the accompanying drawings, is a specification, like reference characters on the 10 drawings indicating like parts in the several figures.

This invention relates to belt shifters and is herein illustrated in connection with a belt shifter which is adapted to receive a belt 15 with equal facility irrespective of whether the shaft from which the belt transmits power is located above, below or at either side of the machine the operation of which the belt shifter controls.

20 The general object of the present invention is to produce an improved belt shifter of the general type indicated above which shall be simple, efficient and inexpensive to manufacture.

25 Referring to the accompanying drawing, the figure illustrates in perspective a portion of a machine in which the present invention is embodied.

The shaft 1 carries the usual fast and 30 loose pulleys 3 and 5 with either of which a belt 7 may be caused to coöperate by being shifted into the proper position. A projection 11 of the bearing 9 of the shaft has a slide bearing to receive a slide rod 13, a 35 handle 15 being provided on one end of said rod to facilitate its manipulation. The other end of the rod 13 is adjustably held by a screw bolt 16 in a socket 17 formed in a boss which is integral with a cylindrical 40 member or ring 19. Carried by the ring 19 is a second ring 21 which is angularly adjustable with respect to said first ring; and carried by the second ring is a shifter member or fork 23 which is adapted to embrace 45 the belt 7. The fork-carrying ring 21 is herein shown as located inside the ring 19 and is held in adjusted position by screw bolts 25 which are threaded through the ring 19 and bear against the periphery of 50 the ring 21.

It should be noted that the diameters of the rings 19 and 21 are each greater than the diameter of either of the pulleys 3 and 5

so that they may pass freely over said pulleys when the slide rod 13 is manipulated. 55

A machine fitted with the belt shifter of the present invention may be readily set up in a factory irrespective of the position of the power shaft from which the belt 7 runs provided, of course, that said shaft is parallel to the shaft 1 of the machine. After the machine has been set up and slide rod 13 adjusted in the socket 17 the ring 21 is adjusted angularly to bring the belt-engaging member 23 into proper position to receive the belt, this position depending upon the location of the power shaft with respect to the shaft 1 of the machine. 65

Having thus described the invention, what I claim as new and desire to secure by Letters Patent of the United States is:

1. The combination with a shaft, a plurality of pulleys mounted thereon, and a belt adapted to coöperate with any selected pulley, of means for shifting said belt from 75 one pulley to another comprising a manually movable member, a ring fastened to said member and arranged to encircle said shaft, a second ring carried by said first ring and angularly adjustable with respect 80 thereto, means for holding said ring in adjusted position, and a belt engaging member carried by said second ring.

2. The combination with a shaft, a plurality of pulleys mounted thereon and a belt 85 adapted to coöperate with any selected pulley, of means for shifting said belt from one pulley to another comprising a manually movable member, a ring fastened to said member and arranged to encircle said 90 shaft, a second ring located inside said first ring and angularly adjustable therein, means for holding said second ring in adjusted position, and a belt-engaging member carried by said second ring. 95

3. The combination with a shaft, a plurality of pulleys mounted thereon and a belt adapted to coöperate with any selected pulley of a movable member having a cylindrical bearing the diameter of which is 100 greater than that of any of the pulleys, a second cylindrical member mounted on said bearing and adjustable angularly with respect to said first member through three hundred and sixty degrees, the diameter of 105 said second cylindrical member being also

greater than that of any of the pulleys, means for holding said second member in adjusted position, and a belt engaging member carried by said second cylindrical member.

4. The combination with a shaft, a plurality of pulleys mounted thereon, and a belt adapted to coöperate with any selected pulley, of means for shifting the belt from one pulley to another comprising a manually movable member, a ring encircling said shaft and adjustable longitudinally of said member, a second ring carried by said first ring and angularly adjustable with respect thereto, and a belt engaging member carried by said second ring.

5. The combination with a shaft, a plurality of pulleys mounted thereon and a belt adapted to coöperate with any selected

pulley, of means for shifting the belt from one pulley to another comprising a slide rod, a ring encircling said shaft and having a boss provided with a socket to receive said rod, means for holding said rod in adjusted position in said socket, a second ring carried by said first ring and angularly adjustable with respect thereto, means for holding said second ring in adjusted position, and a belt engaging member projecting from said second ring.

In testimony whereof I have signed my name to this specification in the presence of two subscribing witnesses.

FREDERICK M. FURBER.
